UNITED STATES PATENT OFFICE.

CHARLES B. TAYLOR, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONTROL SYSTEM FOR PRIME MOVERS.

Application filed June 18, 1924. Serial No. 720,744.

To all whom it may concern:

Be it known that CHARLES B. TAYLOR, a citizen of the United States, residing at Milwaukee, in the county of Milwaukee and State of Wisconsin, has invented a certain new and useful Control System for Prime Movers, of which the following is a specification.

This invention relates to control systems for prime movers and more particularly to means for automatically stopping a prime mover.

One of the objects of the invention is to provide means for closing the gate or other means for controlling the admission of operating fluid to a prime mover and also for controlling the application of a brake thereto. A more specific object is the provision of means whereby the gate of a prime mover will be automatically closed and the brake simultaneously applied. Still another object is the provision of means whereby the aforementioned control means may be readily controllable at any desired distance from the prime mover. A further object is the provision of simple and inexpensive means which is efficient in operation for performing the desired functions. Other objects will appear hereinafter as the description of the invention proceeds.

The novel features of the invention will appear from the specification and the accompanying drawing forming a part thereof and disclosing one embodiment of said invention, and all these novel features are intended to be pointed out in the claims.

Referring to the single figure of the drawings, the prime mover 1 is here shown as a hydraulic turbine adapted to drive a generator 2 through a shaft 3. The admission of water to the turbine is shown as controllable by means of a gate 4. It is however to be understood that the admission of water may be controlled in any other manner as by the usual guide vanes of the turbine. The gate 4 here shown may be operated by means of a crank 5 which is operatively connected to a rod 6 in turn connected to a piston rod 7 associated in this instance with two pistons 8, 9 of a servo-motor here shown as including two separate cylinders in which the pistons 8, 9 operate. The piston 8 may be moved to the left and the piston 9 to the right, thereby respectively closing and open-

ing the gate 4, under the control of a regulating valve 10 adapted to admit fluid under pressure to either one or the other of the cylinders in which pistons 8, 9 operate. The regulating valve 10 is provided with the usual piston valves carried by a rod 11 which is connected in any desired suitable manner to a floating lever 12. This connection is here shown as including a rod 54 suitably pivotally connected at one end with the floating lever 12, and a tubular member 55 connected to the rod 11. The rod 54 extends slidably through a cover for the tubular member 54 and is provided with an end collar 53. A spring 52 is disposed around the rod 54 between the collar 53 and the cover of member 55. The floating lever 12 is pivoted in the usual manner to the fly ball mechanism 13 which is made responsive to the speed of the shaft 3 by any suitable connection, which may be a belt as shown. The outward and inward movement of the fly balls 13 lowers and raises the pivotal point of floating lever 12 in the usual manner to control the regulating valve 10 and therefore the position of gate 4. In order to prevent over travel of the gate 4 in response to a speed regulating effect the usual compensating device 14, which is connected between one end of the floating lever 12 and a crank associated with the gate 4, may be provided.

Fluid under pressure for the operation of the servo-motor may be supplied, through pipe 16, from a pressure supply tank 15, the pressure in which may be produced and maintained by any suitable means.

The rod 11 of the regulating valve is here shown as provided with a projection 17. It will be understood that this projection need not necessarily be on the rod 11 but may be on any part moving in unison therewith. Cooperating with the projection 17 is a lever 18 pivoted at the point 19. The other end of lever 18 is connected through a piston rod 20 to a piston 21 operating in a cylinder 22. The piston 21 is here shown as biased, by means of a spring 51, to a position in which the end of the lever 18 cooperating with projection 17 will place the regulating valve 10 in the gate-closed position thereby admitting fluid under pressure to move piston 8 in the gate-closing direction. The movement of piston 21 is here shown controllable

by means of an electromagnetically operated valve 23 including an operating coil 24 which may be supplied from any suitable source here shown as a battery 25. The circuit of coil 24 may be closed by means of a switch 26 which may be located at any desired distance from any of the other elements.

The electromagnetic valve further comprises a piston-valve 27 operating in a cylinder 28. When the coil 24 is deenergized the piston 27 is adapted to close a port 29 connected by means of a pipe 30 with the pipe 16. Here shown as operating in unison with piston valve 27 is another piston valve 31 which, in the position shown, uncovers a port 32 connected by means of a pipe 33 with a port 34 adapted to admit fluid under pressure to cylinder 22 to thereby force piston 21 against the bias of spring 51 thereby swinging lever 18 in a direction to release the projection 17 and thus freeing the regulating valve 10 for control by means of the fly balls. The piston valve 31 in the position shown, also uncovers a drain port 35 suitably connected with a receiving tank 36. In the position of the parts as shown the spring 51, acting on piston 21, has forced fluid under pressure through pipe 33, ports 32, 35 to the receiving tank 36.

The cylinder 28 is provided with another port 37 suitably connected to a port 38 in a cylinder 39 in which a piston 40 operates. The piston 40 is biased, by means of a suitable spring 41, to move the piston and a piston rod 42 associated therewith in a direction to swing an arm 43 adapted to operate an engineer's valve 44 to its open position. The engineer's valve may also be operated by means of a handle 45. The valve 44 when open is adapted to permit the passage of air (or other fluid) under pressure through a pipe 46 from a pressure tank 47, which may be supplied by an air compressor 48, to one or more brake cylinders 49 thereby setting suitable brake shoes against a brake disk 50 associated with the shaft 3. The brakes may of course be applied to any other rotating parts associated with the turbine or generator.

The operation of the system is as follows. Assuming that the switch 26 is closed, coil 24 will be energized and act to raise piston valves 27 and 31 thereby opening communication between port 29 and port 32 thus admitting fluid under pressure above piston 21 forcing the same downwardly to thereby free the projection 17. At the same time port 29 is in communication with port 37 thereby admitting fluid pressure to cylinder 39 to force piston 40 in a direction to free the engineer's valve 44 so that, as here shown, it may be rotated in a counter-clockwise direction to release air from brake cylinders 49 thereby releasing the brakes. At the same

time piston valve 31 closes port 35 thereby preventing drainage of fluid under pressure to the receiving tank 36. The freeing of projection 17, as previously described, permits spring 52 to expand thereby lifting rod 11 and shifting the regulating valve 10 to the position in which fluid pressure is cut off from piston 8 and admitted against piston 9 thereby moving gate 4 toward the open position. When the turbine 1 starts, 75 the governor 13 controls the regulating valve 10 in the usual manner. If it be now assumed that the turbine is operating at normal speed, the piston 9 having moved the gate 4 to open position, and the switch 26 is then opened, the reverse of the operations previously described will take place, namely, fluid under pressure will be cut off from cylinders 22 and 39 and they will be put into communication with the drain port 35 to 85 the receiving tank 36. Spring 51 will act to move regulating valve 10 to the gate closed position thereby causing piston 8 to close gate 4. At the same time piston 40 will act to operate the valve 44 to set the brakes. 90 The suitable connection between rod 11 and floating lever 12 is here shown as including a spring 52 interposed between a collar 53 on a rod 54, suitably connected to lever 12, and the end of a tube 55 connected to rod 11. 95 The control finger 18 may therefore move rod 11 independently of the position of floating lever 12 by compressing spring 52.

It should be understood that it is not desired to limit the invention to the exact details of construction shown and described, for obvious modifications may occur to persons skilled in the art.

It is claimed and desired to secure by Letters Patent:

1. In a control system for a prime mover, a gate for controlling the admission of operating fluid to said prime mover, a governor responsive to the speed of said prime mover for controlling said gate, means for robbing said governor of control of said gate and for causing said gate to close, a brake for said prime mover, means for applying said brake, and common means for controlling said means for robbing said governor of control and said brake-applying means.

2. In a system for stopping a prime mover, a gate for controlling the admission of operating fluid to said prime mover, a servomotor for operating said gate, a regulating valve for controlling said servomotor, means for moving said regulating valve to gate-closed position, a brake for said prime mover, means for applying said brake, and common means for controlling said means for moving said regulating valve to gate-closed position and said brake-applying means.

3. In a system for stopping a prime mov-

er, a gate for controlling the admission of operating fluid to said prime mover, a supply of fluid under pressure, means for closing said gate including means normally biased to gate-closed position and held out of said position by said fluid pressure, a brake for said prime mover, means including fluid pressure operated means for causing application of said brake, and means for cutting off said supply of fluid pressure.

4. In a system for stopping a prime mover, a gate for controlling the admission of operating fluid to said prime mover, a servomotor for operating said gate, a regulating valve for controlling said servo-motor, means for biasing said regulating valve to gate-closed position, fluid pressure operated control means for acting against said biasing means, a brake for said prime mover, fluid pressure operated means for applying said brake, means for controlling the supply of fluid pressure to said brake-applying means biased to brake-applying position, fluid pressure operated control means for acting against said bias, and means for controlling said fluid pressure control means.

5. In a control system for a prime mover, a gate for controlling the admission of operating fluid to said prime mover, a servomotor for operating said gate, a regulating valve for controlling said servo-motor, a governor responsive to the speed of said prime mover for controlling said regulating valve, means for robbing said governor of control of said regulating valve and for causing said regulating valve to move to the gate-closed position, a brake for said prime mover, means for applying said brake, and common means for controlling said means

for robbing said governor of control and 40 said brake-applying means.

6. In a control system for a prime mover, a gate for controlling the admission of operating fluid to said prime mover, a servomotor for operating said gate, a regulating valve for controlling said servo-motor, a governor responsive to the speed of said prime mover for controlling said regulating valve, means biased to rob said governor of control of said regulating valve and for 50 causing said regulating valve to move to the gate-closed position, means for overcoming said bias, a brake for said prime mover, means for applying said brake, and common means for controlling said bias-overcoming 55 means and said brake-applying means.

7. In a control system for a prime mover, a gate for controlling the admission of operating fluid to said prime mover, a servomotor for operating said gate, a regulating valve for controlling said servo-motor, a governor responsive to the speed of said prime mover for controlling said regulating valve, means biased to rob said governor of control of said regulating valve and for 60 causing said regulating valve to move to the gate-closed position, fluid pressure operated means for overcoming said bias, a brake for 65 said prime mover, fluid pressure operated means for controlling the application of 70 said brake, and common means for controlling the supply of fluid pressure to said bias-overcoming means and said brake-application controlling means.

In testimony whereof, the signature of the 75 inventor is affixed hereto.

CHARLES B. TAYLOR.
